(57) **CLAIM**

The ornamental design for a container for oral care tablets as shown and described.

DESCRIPTION

FIG. 1 is a perspective elevation view of a container for oral care tablets;

FIG. 2 is a front view thereof;

FIG. 3 is a right side view thereof;

FIG. 4 is a back view thereof;

FIG. 5 is a left side view thereof;

FIG. 6 is a top view thereof; and

FIG. 7 is a bottom view thereof.

FIG. 8 is a perspective elevation view of a second embodiment of container for oral care tablets;

FIG. 9 is a front view thereof;

FIG. 10 is a right side view thereof;

FIG. 11 is a back view thereof;

FIG. 12 is a left side view thereof;

FIG. 13 is a top view thereof; and

FIG. 14 is a bottom view thereof.

FIG. 15 is a perspective elevation view of the second embodiment of container for oral care tablets with unclaimed tablets;

FIG. 16 is a front view thereof;

FIG. 17 is a right side view thereof;

FIG. 18 is a back view thereof; and

FIG. 19 is a left side view thereof;

FIG. 20 is a top view thereof; and,

FIG. 21 is a bottom view thereof.

The broken dashed lines showing of a container's neck and cap in the drawings illustrate portions of the container for oral care tablets that form no part of the claimed design. The broken dashed line showing tablets illustrate environmental structures that form no part of the claimed design.

1 Claim, 9 Drawing Sheets
